UNITED STATES PATENT OFFICE.

WALTER N. MECKLAN, OF OLEAN, NEW YORK.

DESIGN FOR A BOLSTER-CIRCLE.

SPECIFICATION forming part of Design No. 35,392, dated December 3, 1901.

Application filed October 30, 1901. Serial No. 80,568. Term of patent 14 years.

To all whom it may concern:

Be it known that I, WALTER N. MECKLAN, a citizen of the United States, residing at Olean, in the county of Cattaraugus and State of New York, have invented and produced a new and original Design for a Bolster-Circle, of which the following is a specification.

This invention relates to a new and original design for a bolster-circle for application to the running-gear of wagons and other vehicles, and the essential features reside in the design as illustrated in the accompanying drawing, wherein a perspective view of a bolster-circle embodying the design is shown.

15 The design is characterized by an approximately semicircular top body portion 1, having a front compound curved wall 2 with a central forwardly-extending convex projection 3. Depending from the opposite sides 20 of the body 1 are members 4, of concavo-convex shape, having compound curved outer edges 5, which are joined at their lower extremities by a cross connection 6, having the

front wall of the same shape as the wall 2 of the body above, a space or opening 7 being 25 formed between the body and connection and having end curved walls 8. The upper and lower portions of the members 4 have circular openings 9 therein, and extending through the projection 3 of the body 1 is an opening with 30 an upper tubular extension 10, which aligns with an opening 11 through the corresponding portion of the connection 6 below. Extending laterally from the body 1 are converging arms 12 with outer rounded terminals 13. 35

Having thus described the invention, what is claimed as new is—

The design for a bolster-circle, as herein shown and described.

In testimony that I claim the foregoing as 40 my own I have hereto affixed my signature in the presence of two witnesses.

WALTER N. MECKLAN.
